CLAIM

The ornamental design for the plastic bag for frozen food storage, as shown and described.

DESCRIPTION

FIG. 1 is a perspective view of a plastic bag for frozen food storage showing our new design;

FIG. 2 is a right end elevation view thereof;

FIG. 3 is a left end elevation thereof;

FIG. 4 is a right side elevation thereof;

FIG. 5 is a left side elevation view thereof;

FIG. 6 is a top view of the plastic bag shown in FIG. 1; and,
FIG. 7 is a bottom view of the bottle of FIG. 1.

The bag is shown fragmented to represent an indeterminate length.
